UNITED STATES PATENT OFFICE.

ALFRED OTTO, OF TAYLOR, AND ROBERT OTTO, OF LEE COUNTY, TEXAS.

SIGN-LETTER PLATE.

Application filed April 27, 1926. Serial No. 104,978.

This invention relates to certain new and useful improvements in sign letter plates, and has special reference to sign letter plates of that type designed to be electrically illuminated, and to sign letter plates which, while adapted to be illuminated, will show in the dark even when not illuminated.

One object of our invention is to provide a sign letter embodying a novel and improved construction of sign plate and light reflecting means.

Another object of our invention is to provide a sign letter embodying a molded open frame letter or character and novel means for fastening it to a stencil plate.

Still another object of our invention is to provide a sign letter embodying a stencil plate and a translucent backing plate and embodying novel means for securing the translucent backing plate in position, so as to admit of the ready removal of the backing plate for cleaning it or for the substitution of a new backing plate for an old one when the latter is broken or a change in backing plates is desired.

With these and other objects in view, the invention consists of the features of construction, combination and arrangement of parts, hereinafter fully described and claimed, reference being had to the accompanying drawings, in which:—

Figure 1 is a face view of one form of sign letter embodying our invention.

Figure 2 is a rear elevation of the same.

Figure 3 is a section on line 3—3 of Figure 1.

Figure 4 is a section on line 4—4 of Figure 2.

Figures 5 and 6 are fragmentary perspective views, in cross-section, of different forms of open character frame mouldings.

Figures 7 is a detail section showing the application of a character formed of the moulding illustrated in Figures 6.

In the practical embodiment of our invention as shown in Figures 1 to 5, inclusive, we provide a sign letter plate comprising a metallic stencil plate 1, made of zinc or other suitable material, an open frame sign character 2, made of cast metal, and a translucent backing plate 3, made of opal or other suitable glass, designed to permit of the passage of light rays and to form an ornamental panel showing through the opening in the open frame sign character 2.

The plate 1 is of rectangular or oblong

rectangular form and has its side edges provided with marginal rearwardly extending flanges 4, providing on the rear side of said plate a housing or enclosure for the backing plate 3. These flanges 4 are provided with tongues or other fastening members 5 for fastening the sign letter plate to a sign frame of any suitable construction. The character 2 is preferably cast from an alloy or composition metal which is rust proof and has light reflecting qualities, although, if desired, any suitable material may be used and the character painted or enameled to give it the stated properties. The character 70 is so formed that it marginally bounds the opening 6 in the plate 1, through which the plate 3 is exposed, which opening 6 and the associated open frame character 2 provide the desired configuration of sign letter or 75 character to be displayed. Moulded in the sign character 2 at suitable points are fastening members 7, herein shown in the form of staples. The head portions of these staples are fixed in the metal of the character while the prongs thereof project from the rear face of the character and are designed to be passed through openings 8 in the plate and clenched upon the back of the plate to fasten said sign character in position. The portions of the character 2 may be moulded in any desired cross-sectional shape. As shown in Figures 1 to 5, inclusive, the character mould strips or portions are of substantially triangular form 90 in cross-section so as to provide a cameo type of character having a prismatic reflecting surface.

In Figures 6 and 7 a character 2' of modified cross-sectional form is shown, the portions or mould strips of said character being substantially of oval or elliptical form in cross-section and presenting outwardly and inwardly projecting ribs 9 and 10 and a central flange 11 lying upon its outer face. 100 With this construction, the flanged part 9 projects outwardly to form the face of the character, while the flanged portion 10 projects through the opening 6 into the housing to form a seat face or abutment for the backing plate 3, and the flange 11 overlaps the front of the plate 1. This flange 11 serves as an attaching flange which may be soldered or otherwise secured to the plate 1. As a result of this construction a deep 110 framed sign character is produced, which will reflect the light rays to a maximum

extent, and which may be advantageously used under some conditions.

The translucent plate 3 is held within the housing of the plate 1 by a frame construction composed of angle metal retaining strips 12. These strips are equal in number to the sides of the plates 1 and 3, the plate 1 being of sufficiently greater dimensions than the plate 3 to provide space for the reception 10 of a strip 12 between each of its flanges 4 and the adjacent edge of the plate 3. Each strip 12 comprises a body portion 13 lying parallel with the plate 1 and secured thereto and a flange portion 14 projecting at right 15 angles to the plate 2 and forming a bearing or abutment against which the adjacent edge of the plate 3 is adapted to rest. The flanges 14 of the respective strips 12 are longitudinally slitted in the region of their end portions 20 and for a suitable distance inwardly therefrom, to provide bendable retaining fingers 15. These fingers 15 are adapted to be bent inwardly at an angle to the plane of the flanges, as shown in Figure 2, so as 25 to overlie the back of the plate 3 and serve as holding or retaining members to fasten said plate in position. By this means the plate 3 will be securely confined against displacement or rattling, but upon bending the 30 fingers 15 back to normal position may be released for removal. Provision is thus made to adapt the plate 3 to be detached for cleansing purposes whenever desired or for the substitution of a new plate in place 35 of a damaged one or whenever it is desired to substitute a different type of translucent plate for that which has been in use. Sign plates constructed in the manner shown and described may be assembled upon a sign 40 frame to provide a complete sign bearing the desired sign matter. The sign plates on this sign frame may be electrically illuminated at night, but, by the use of suitable bright metals in the formation of the metallic member in connection with proper 45 translucent backing plates, or by painting or enameling the metallic members in a suitable manner, a sign structure may be produced which will show clearly in the dark 50 even when not illuminated.

From the foregoing description, taken in connection with the accompanying drawings, the construction and mode of operation of our improved sign letter plate will be readily understood and its advantages appreciated. While the constructions shown, for example, 55 are preferred, it is to be understood, of

course, that changes in the form, construction and dimensions of parts may be made within the scope of the appended claims, without departing from the spirit or sacrificing any of the advantages of the invention.

Having thus fully described our invention, we claim:—

1. A sign comprising a sheet metal stencil plate having a perforate portion delineating a sign character and provided with marginal rearwardly extending flanges forming a rear housing, an open frame sign character disposed upon the face of said plate, retaining members upon the rear of said plate within the space bounded by said housing, said retaining members having rearwardly extending flanges, and a backing plate disposed between said retaining members and marginally engaged thereby, said retaining members having bendable fingers adapted to be projected over upon said backing plate to hold the same in position. 60

2. A sign comprising a sheet metal stencil plate, a translucent backing plate, a frame upon the stencil plate having abutment flanges extending rearwardly at right angles to and marginally engaging said backing plate, and fingers upon said flanges formed by longitudinally slitting the same and adapted to be bent inward laterally over upon the backing plate to retain the same in position. 70

3. A sign comprising a sheet metal stencil plate having marginal flanges forming a housing at the rear of said plate, a translucent backing plate, a frame secured to the stencil plate within said housing and having abutment flanges extending rearwardly at right angles to and marginally engaging said backing plate, and fingers upon said flanges formed by longitudinally slitting the same and adapted to be bent inward laterally over upon the backing plate to retain the same in position. 80

4. A sign comprising a sheet metal stencil plate, a backing plate upon the rear of said stencil plate, retaining members projecting at right angles from the stencil plate and marginally engaging said backing plate, and retaining fingers upon said members formed by longitudinally slitting the same and adapted to be bent inwardly at an angle thereto and over upon the backing plate. 90

In testimony whereof we affix our signatures.

ALFRED OTTO.
ROBERT OTTO.
